DEVICE TO TEST SYNCHRO CIRCUIT AND
SYNCHRO EQUIPMENT

Baldwin W. Ridley, Valley Stream, N. Y.

Application July 3, 1945, Serial No. 603,099

11 Claims. (Cl. 177—337)

(Granted under the act of March 3, 1883, as
amended April 30, 1928; 370 O. G. 757)

1

This invention relates to an instrument and method for testing the transmitter and repeater units and the circuits of an electrical synchro type of signal transmitting system.

An object of this invention is to provide a self contained, portable instrument by means of which synchro units and circuits can be accurately tested in their installed environment.

Another object is to provide an inexpensive testing device that will obviate the need for using a "standard" synchro in testing synchro systems.

A further object is to provide a testing instrument with which a relatively unskilled operator can test for and rectify defects in a synchro system merely by following visual indicia on the instrument that automatically indicate the source of the defect and the means for the correction thereof.

Still another object is to provide a device for testing and setting a synchro unit on electrical zero.

A still further object is to provide an electrical circuit means for controllably rotating a synchro unit and which will transmit and receive synchro signals.

Further objects and advantages of this invention, as well as its construction, arrangement and operation, will be apparent from the following description and claims in connection with the accompanying drawings, in which,

Figure 1 is a front elevation of the test instrument showing the instrument panel and visual indicia thereon.

Figure 2 is a circuit diagram of the test instrument.

Figure 3 is a simplified circuit diagram of the test circuit as applied to a synchro unit under test.

Figure 4 is a view of a typical synchro unit.

Figure 5 is a circuit diagram of a standard synchro signal transmitting system.

Figure 6 is a diagrammatic illustration of the voltages induced in the stator windings of a synchro unit as the rotor is turned.

Figure 7 is a diagrammatic view of the instrument panel shown in Figure 1 with the pertinent portions of the analyzing chart shown in the position they would occupy in analyzing a circuit defect.

Figure 8 is a detailed view of the analyzing chart employed in the test instrument.

Figure 9 is a phantom view of a portion of the test instrument shown in Figure 1 showing the sliding mark and its relation to the analyzing chart and reversing switch.

Figures 10 to 13 inclusive illustrate the various

2

observable symptoms in a synchro unit in which electrical shorts exist in the stator windings of a synchro unit under test.

Figures 14 to 17 inclusive illustrate the symptoms apparent when an open circuit exists in the stator windings of a synchro unit under test.

Figure 18 shows the test circuit for the electrical zero alignment test, and

Figures 19 to 23 inclusive illustrate the various conditions of crossed stator windings.

In the former method of testing synchro units a standard synchro unit is used. By noting the behavior of the device being tested when driven by such standard, the device under test may be checked for open circuits, short circuits, and reversed circuits, etc. The standard synchro unit is relatively expensive and unobtainable and, moreover, requires a skilled, trained operator, who can sense and analyze the behavior of the synchro under test when being driven by the standard. A standard synchro, moreover, is quite delicate in construction and can not be subjected to abuse in handling as often occurs in use aboard ship.

25 The test instrument comprising this invention is designed to replace the standard test synchro in conducting synchro tests. It consists only of an electrical wiring circuit containing a series of indicating lights and switches and a visual

30 analyzing or trouble shooting chart. It is therefore light and rugged in construction, easily portable and inexpensive. It is so arranged that an inexperienced operator can detect and rectify synchro circuit defects merely by reading the

35 visual indicia provided on the instrument panel. There is shown in Figure 1 the test device comprising the invention. The device consists of an instrument box having a panel 1 on which there is mounted a series of differently colored indicating lights 2, 3, 4 and 5. Light 2 is preferably blue and is designated as the Electrical zero indicating light. Lights 3, 4 and 5 are respectively red, green and amber in color and are called the rotation indicating lights. The panel of the instrument box 1 has an opening or sighting slot 6 for visual access to the interior of the instrument box. A transparent cover 6a of glass or other material covers the slot 6.

A drum 7 is rotatably mounted within the instrument box by means of an axle 16 mounted in a pair of discs 1c—1c with its surface adjacent the opening 6, and an indicating chart 8, which is shown in detail in Figure 8 is secured to the periphery of the drum so that the symbols 45 on the chart 8 can be seen through the opening 6. The drum is manually rotated by a knurled

50 55

knob 7a. The region of the panel adjacent the slot or opening 6 is suitably inscribed as shown with a number of visual indicia columns or legends. The various legends are in tabulated form with each row related to a cooperating row on the chart 8 as will be more fully explained. Each of the rows inscribed on the instrument panel 1 will be referred to by numerals 11, 12, 13, 14 and 15 respectively.

The chart as shown in detail in Figure 8 of the drawings consists of 12 vertical columns (labelled A to L), and five horizontal rows (labelled 11 to 15) corresponding with the visual indicial rows on the instrumental panel 1 (Figure 1). Each of the vertical columns of chart 8 bears two headings reading in degrees between 0° and 360° in steps of 30°. The uppermost headings increase in value as read to the right and the lower headings decrease in value. The uppermost heading is used in testing synchro units that have increasing dial scale readings with clockwise rotation, while the lower heading applies to synchro units designed for counterclockwise rotation, in which the dial scale readings increase with counter-clockwise rotation of the synchro. Underneath the printed rows (11 to 15) are three colored bands of varying widths separated from each other by colorless margins. These bands are respectively red, green and amber in color as shown in Figure 8 and the width of each strip at any point along the chart represents the relative intensity of the corresponding indicating light, 3, 4, or 5 with which these color bands are aligned as shown in Figures 1 and 7.

Mounted on the panel of the instrument box 1 are a reversing switch 16, a zero lock switch 17 and a pair of push-button switches 18 and 19. These switches as well as the indicating lights are in the test circuit otherwise enclosed within the instrument box and illustrated diagrammatically in Figure 2. The test circuit comprises end terminals R₁—R₂ and S₁—S₂—S₃. Indicating lamp 5 (amber) is connected across terminals S₂—S₃ by leads 20 and 21 and green indicating light 4 is connected across terminals S₁—S₂ by leads 21 and 22. Red indicating light 3 is connected across terminals S₁—S₃ by leads 20, 22 and 23. Terminal R₂ is connected by lead 24 to zero lock switch 17 and blue indicating light 2 is connected in series with this lead together with a series resistance 25. The zero lock switch 17 when closed connects terminal R₂ to terminal S₃ through leads 26, 23 and 20 and to terminal S₁ through extension lead 22a of lead 22. Switch 17 is a conventional double-pole toggle switch with its common terminal shorted by a jumper 17a.

The circuit is provided with means for electrically shorting terminals S₁—S₂ or terminals S₂—S₃. With switch 16 in "normal" position, S₂ is connected through leads 21 and 27, push-button switch 18, lead 28, switch 16, and leads 30, 26, 23, and 20 to S₃, or through lead 21, push-button switch 19, lead 29, switch 16, and lead 22 to S₁. On the other hand, with switch 16 in "reverse" position, S₂ is connected through leads 21 and 27, push-button switch 18, lead 28, switch 16, and lead 22 to S₁, or through lead 21, push-button switch 19, lead 29, switch 16, and leads 30, 26, 23, and 20 to S₃. The purpose of "reversing switch" 16 is to permit use of push-buttons 18 and 19 to effect changes (as indicated on panel 1 adjacent to said push-buttons) in the

5 dial reading on the synchro being tested, the switch position being selected according to whether said dial readings increase with clockwise ("normal") or counter-clockwise ("reverse") rotation of the synchro.

The end terminals R₁—R₂ and S₁—S₂—S₃ shown in the circuit diagram of Figure 2 are brought to the outside of the instrument box as shown in Figure 1 and suitable extension leads having similar designation are connected thereto for use in testing synchro circuit installations. In actual service installations all synchro units are connected to terminal blocks such as indicated by numeral 30b in Figure 2 and the connecting leads on the terminal block are labelled with the standard synchro lead designations, namely R₁—R₂ as the rotor leads and S₁—S₂—S₃ as the three stator leads. A synchro unit comprising the stator winding leads S₁—S₂—S₃ and rotor leads R₁—R₂ is shown in the circuit diagram of Figure 2 connected to the test instrument circuit through terminal block 30b.

A synchro unit is illustrated in Figure 4 and a typical synchro signal transmitting system comprising similar transmitter and receiver units is shown in Figure 5 of the drawings. As shown in Fig. 4, the usual type of synchro unit consists of a housing 31 in which there is rotatably mounted a rotor unit to which the indicating dial 32 is fixed to rotate therewith. The synchro unit shown in Figure 4 is designed for clockwise rotation and is suitably inscribed so that the numerical value in degrees inscribed on the dial 32 will increase with clockwise rotation. External leads S₁—S₂—S₃ and R₁—R₂ are connected to the stator and rotor elements respectively of the synchro unit 31. Standard terminology is employed to denote the various circuits of all synchro units as shown in Figure 5, to facilitate and standardize wiring installation. Thus the three stator coils or windings of each synchro unit are denoted by S₁, S₂ and S₃ respectively as shown in Figure 5 whether or not a transmitter or repeater unit is being referred to. Similarly the rotor winding terminals are labelled as R₁—R₂ as shown. The typical transmitter and receiver unit circuit diagram is shown in Figure 5 to illustrate later discussion. An index 33 (Figure 4) is provided on the mounting panel or case (not shown) in which the synchro is mounted as a reference point of rotation.

The test instrument of this invention employs a series of indicating lights together with a self-explanatory defect-indicating visual indicia table used in conjunction with a rotatable analyzing chart mounted in alignment therewith so that setting of the analyzing chart in response to an observed abnormal behavior of the instrument under test will automatically indicate in legend form the nature of the defect causing such abnormality.

The test instrument described above is used to locate and rectify the various defects commonly found in an electrical synchro signal transmitting system. These defects include the following:

1. Electrical opens in synchro-unit rotor circuit,
2. Electrical shorts in synchro-unit stator circuit,
3. Opens in synchro-unit stator circuit,
4. Electrical zero alignment test,
5. Stator circuit wiring reversed or mixed,
6. Rotor circuit wiring reversed.

In the following disclosure the apparent effects caused by the presence of each of the above defects in a synchro system will be described to-

gether with the manner in which the test instrument of this invention detects and rectifies such defects. In conducting the test, the instrument is connected to the terminal block 30b as shown in Figure 2 with the test leads R₁—R₂, and S₁—S₂—S₃ from the instrument box connected to correspondingly labelled terminals on the terminal block at the particular point in the synchro system at which the test is to be conducted. It will therefore be seen, from an inspection of the circuit diagram of Figure 2 that the synchro unit under test is connected in the test circuit in accordance with the simplified test circuit diagram shown in Figure 3 of the drawings.

Red indicating light 3 (Figure 3) is connected across synchro unit stator terminals S₁—S₃; green indicating light 4 is connected across stator terminals S₁—S₂ and; amber light 5 is connected across stator terminals S₂—S₃. Terminal R₁ of the synchro rotor is connected to S₂, and terminal R₂ is connected in series with blue indicating light 2 and resistance 25 to S₁ and S₃ through zero lock switch 17. It is also apparent from this figure that by closing reversing switch 16 in either direction and actuating either push button 18 or 19, terminals S₁—S₂ and S₂—S₃ respectively can be electrically shorted. The reversing switch 16 is used in connection with the push button switches 18 and 19 selectively to change the position of the rotor of the synchro under test, so that the legends on panel 1 adjacent said push-button switches may be coordinated with dial readings on said synchro that increase with either clockwise ("normal") or counter-clockwise ("reverse") rotation, as the case may be. The rotor is excited from an A. C. power source connected to terminals R₁—R₂ as shown. The construction of a synchro includes the three-phase wye-connected stators S₁, S₂ and S₃ (Figure 5) and the rotatable A. C. excited rotor R₁—R₂. Rotation of the rotor member R₁—R₂ of either the transmitter or repeater units induces a sinusoidally varying current in each of the stator windings which is graphically shown by the curves of Figure 6 in which each curve shows the magnitude of the voltage in any one stator winding for a given position of the rotor R₁—R₂.

Inasmuch as the indicating lights 3, 4 and 5 are connected across terminals S₁—S₃, S₁—S₂ and S₂—S₃, respectively, (Figure 3) the magnitude of the voltages across these terminals as the rotor R₁—R₂ is rotated, will be indicated by the intensity of each of these lights, thereby visually representing the voltage curves of Figure 6. The sequence in which these lights vary from dim to bright can therefore be used as a check for the proper rotation of a synchro unit in a manner subsequently to be described.

In conducting a test, the analyzing chart 8 (Figure 8) mounted on the periphery of the rotatable drum 7 is used in connection with the visual indicia or legends arranged in column form adjacent the sighting slot 6 on the instrument panel, and identified by numerals 11, 12, 13, 14 and 15 in Figure 1. The analyzing chart 8 is shown in detail in Figure 8. As shown it consists of 12 vertical columns identified by letters A, B, C, D, E, F, G, H, I, J, K, and L and a number of horizontal rows 11, 12, 13, 14 and 15 which correspond respectively to the legend rows 11, 12, 13, 14 and 15 inscribed on the face of the instrument panel (Figure 1). The two topmost horizontal rows labelled in Figure 8 (Synchro dial reading set here) appear opposite the inscription "Set indication here" at the top of the sighting slot 6 on

the panel 1 (Figure 1). For purposes of illustration a portion of the instrument panel 1 (Figure 1) has been shown in Figure 7 with the pertinent portions of the analyzing chart 8 (Figure 8) 5 namely columns A, C, E, G, I and K shown as they would appear in sighting slot 6 on the instrument box (Figure 1) when the drum 7 is rotated to a given position in a manner later to be described. It will be seen from Figure 7 that by 10 reading across any selected visual indicia row a statement of defect can be read. For example, if column E were to appear in the sighting slot 6 (Figure 1), reading across row 12 in Figure 7 there would be seen the statement "Dial locks at position indicated S₂—S₃ in stator shorted." This 15 means that if the test instrument were used in a manner later to be described, the above visual statement would make apparent that stator windings S₂ and S₃ are shorted as in Figure 11 and the operator would immediately know what defect in the synchro unit under test should be corrected. In a similar manner, the other columns are used 20 to visually indicate various other defects as will become apparent in later portions of the specification.

The first two horizontal or heading rows (Figures 7 and 8) of the analyzing chart 8 appearing opposite (synchro dial readings are set here) both are marked in degrees, the first commencing 25 with 0 degrees and increasing in value or corresponding to clockwise rotation of the synchro-unit dial 32 (Figure 4), the second decreasing in value or corresponding to counter-clockwise rotation of the synchro dial 32. When the reversing switch 16 is in the "normal" position, a slidable mask 34 connected to the operating handle of the 30 reversing switch 16 is thrown across the sighting slot 6 (Figure 1). Such action is illustrated in Figure 9 in which the reversing switch 16 is shown in "normal" position. The slidable mask 34 is slidably mounted on the under face of the test panel 1. An aperture 35 adjacent one end of the mask 34 fits over the switch handle 16a so that the mask will slide back and forth as the switch 35 handle 16a is thrown from "normal" to "reverse" positions. In the normal position the offset portion of the mask 34a will cover the lower row of figures on the chart 8 as shown in Figure 2 so that the top row of figures will be visible through 40 the sighting slot 6. Similarly when the handle 16a of switch 16 is thrown to the "reverse" position, the mask 34 will be slid to the right so that the top row of numerals is masked and the second row visible through the sighting slot 6. The purpose of this arrangement is to adapt the test instrument to test synchros designed for either clockwise or counter-clockwise rotation. Switch 16 is set in "normal" position for the former, with the mask 34 uncovering the topmost heading on 45 chart 8 and is thrown to "reverse" position in testing the latter types of synchros with mask 34 exposing the second row of figures.

1. TESTING FOR AN OPEN OR SHORT IN THE ROTOR CIRCUIT

If there is an open in the rotor coil circuit none of the indicating lights 2, 3, 4 or 5 will be energized (Figure 3); moreover there will be no torque in the rotor R₁—R₂ and the entire synchro unit will not be energized.

The presence of an electrical short in the rotor circuit would be apparent as soon as the synchro unit were connected to the power source as a short circuit would be set up.

2. TESTING FOR SHORTS IN THE STATOR CIRCUIT

A short circuit in the stator winding will be indicated by the fact that the dial 32 on the indicating unit (Figure 4) under test will lock in any one of 6 positions depending upon which of the stator windings are shorted, when the synchro is connected to a power source. The reason for this can be seen by referring to Figures 10, 11, 12 and 13 of the drawings which show a typical stator winding with stator coils S_1-S_2 , S_2-S_3 and S_1-S_3 respectively shorted. With coils S_1-S_2 shorted as in Figure 10, there will be no voltage across these two terminals and indicating light 4 (Figures 2 and 3), which is connected across these terminals, will be out; the lights 3 and 5 will burn with equal intensity. The rotor will take a position as shown in Figure 10 aligned with coil S_3 such that the dial 32 (Figure 4) will read 240 or 60 degrees. The drum 7 in the instrument box (Figure 1) is then rotated by means of the knurled knob 7a until the top row of figures (reading in degrees) on the chart 8 corresponds to the corresponding synchro-unit reading at which the dial stopped—i. e., either 60 or 240 degrees. This has been shown in Figure 7 of the drawings which is a diagrammatic illustration of the instrument box of Figure 1 with the pertinent columns of the analyzing chart 8 shown in their relation to the visual indicia columns on the instrument panel 1 as they would appear in the sighting slot 6 when the drum 7 is set. Thus, for the condition outlined above, should the dial lock at 60°, the drum would be manually rotated until column C (Figure 7) appeared in slot 6 on the instrument panel with numeral 60 opposite "Set indication here." Reading across the visual indicia column 12 "Dial locks at position indicated S_1-S_2 in stator shorted" would be read. By this means, an operator would immediately ascertain the defect in the synchro unit under test and would know the remedy. Similarly if S_2-S_3 were shorted as in Figure 11, light 5 (Figures 2 and 3) would be out and the rotor would assume a position aligned with coil S_1 corresponding to 120 or 300 degrees as shown. If it were 120 degrees, then the drum would be turned until column E (Figure 7) were opposite "Set indication here" and column 12 would read "Dial locks at position indicated S_2-S_3 in stator shorted." Similarly with the condition illustrated in Figure 12 in which S_1-S_3 are shorted indicating light 3 would be out, and the dial would lock at either 0 or 180 degrees and the columns A or G, Figure 7 would indicate the defect.

With all three windings shorted as in Figure 13 no torque would be evident on the synchro unit and all the indicating lights 3, 4 and 5 (Figures 1, 2 and 3) would be out.

3. TESTING FOR AN OPEN CIRCUIT IN THE STATOR CIRCUIT

An open may exist in any one or all of the stator windings S_1 , S_2 or S_3 as shown in Figures 14, 15, 16 and 17 of the drawings. The presence of an open circuit in the stator winding would be made apparent upon rotating the synchro unit under test either manually or by the push-button switches 18 and 19, by the fact that indicating lights 3, 4 and 5 (Figures 1 and 7) would not operate in proper alternate sequence as previously described in connection with Figure 6 of the drawings, but would simultaneously increase and decrease in intensity as the rotor of the synchro

unit were turned. By noting the position of the synchro rotor when all three of the indicating lights are out, and making use of the rotating drum 7 and appropriate visual indicia row 11 in Figures 1 and 7) the open circuit can be detected in the following manner:

a. Field winding S_1 open as in Figure 14

In this case, all three indicating lights 3, 4, and 5 will be out when the rotor R_1-R_2 is in a 120° or 300° position as shown in Figure 14 because S_1 being open, there is no voltage across lights 3 and 4, and the voltage across light 5 is almost zero since the flux from rotor R_1-R_2 is almost entirely transverse to coils S_2 and S_3 . Rotating drum 7 (Figure 1) so that either column E or K of chart 8 (Figure 7) appears in the sighting slot 6, visual indicia row 11 (Figure 7) will indicate that coil S_1 is open.

b. Field winding S_2 open as in Figure 15

All three indicating lights 3, 4 and 5 will be out with rotor R_1-R_2 in a 0° or 180° position as in Figure 15 for reasons similar to those stated in (a) above and columns A or G on chart 8 will indicate that coil S_2 is open when visual indicia row 11 is read (Figure 7).

c. Field winding S_3 open as in Figure 16

The three indicating lights 3, 4 and 5 in this case will be out with rotor R_1-R_2 in a 60 or 240° position as shown in Figure 16 and columns 11 and either C or I on chart 8 (Figure 7) will indicate that stator winding S_3 is open.

d. Two or more field windings open as in Figure 17

In this case there will be no voltage across any of the indicating lights 3, 4, or 5 as the rotor R_1-R_2 is turned, regardless of the position of the rotor because there is no electrical continuity in the stator circuit.

4. ELECTRICAL ZERO ALIGNMENT TEST

In order to have a definite position at which to set the dial 32 of the synchro unit (Figure 4) a definite phase relation between the dial in relation to the rotor must be established. That is, a position must be established whereby the dial will indicate zero at a predetermined rotor position so that all synchro units used in a system will correspond. This position is known as "electrical zero" and is defined as "Electrical zero is that position of the rotor with respect to the stator in which there is no voltage induced in stator coils S_1 and S_3 and the voltage across the rotor terminals R_1-R_2 is in phase with the equal voltages across S_2-S_1 and S_2-S_3 respectively." To satisfy this condition the rotor R_1-R_2 will occupy a position with respect to stator windings S_1 , S_2 and S_3 as shown in Figure 18 and the dial 32 will be positioned on the rotor so that its zero mark will be opposite the reference mark 33 as shown in Figure 4.

The electrical zero test is performed by throwing switch 17 to the "zero lock" position as indicated in Figure 1 of the drawings. The circuit of Figures 2 or 3 with switch 17 closed may be illustrated in simplified form as in Figure 18. With the synchro unit connected in this manner the rotor R_1-R_2 will lock electrically in one of two positions, 0 or 180 degrees because there is no voltage across S_1-S_3 . Should blue indicating light 2 (Figures 1 and 18), light with the rotor R_1-R_2 in this position, the rotor is 180 degrees from electrical zero. By rotating the rotor

$R_1 = R_2 = 180$ degrees from this position, light 2 will go out. This position is electrical zero. The purpose of resistance 25 is to prevent lamp 2 from burning out in the 180 degree position and insure that the 115 volt lamp 2 will not glow at the lower voltage which exists in the electrical zero position. When the synchro rotor $R_1 - R_2$ is at the 180 degree position the rotor and stator voltages are additive. The ratio of the stator to the rotor windings is 115 to 78 for a standard synchro unit and the lamp 2 will have 193 volts impressed on it and will light. At electrical zero, the rotor and stator voltages are opposed so that only 37 volts is impressed on light 2 and resistance 25 so that the former will not light.

The electrical-zero alignment test is performed as follows:

(a) Switch 17 (labeled 0-180 in Fig. 1) is thrown to "zero lock" position. If R_1 and R_2 in the synchro circuit are properly connected the dial 32 on the synchro unit under test will lock at either 0 or 180 degrees. At 0 degree the blue indicating light 2 will be out and at 180 degrees it will light as above stated.

(b) If, however, the opposite should happen and blue indicating light should light when the dial locks at 0° and be out when the latter locks at 180°, then, by rotating drum 7 until the heading 180° appears in sighting slot 6, visual indicia row 15 in the instrument panel 1 would read "If indication appears here $R_1 - R_2$ (from column G, Figure 7) in rotor reversed." The defect and remedy is accordingly made apparent.

5. STATOR CIRCUIT WIRING REVERSED OR MIXED

The stator winding circuit of the synchro unit under test may be mixed up or crossed as follows:

- a. S_1 and S_2 may be reversed as in Figure 19.
- b. S_2 and S_3 may be reversed as in Figure 20.
- c. S_1 and S_3 may be reversed as in Figure 21.
- d. S_1 and S_2 , S_2 and S_3 , and S_3 and S_1 may be mixed as in Figure 22.
- e. S_1 and S_3 , S_2 and S_1 , and S_3 and S_2 may be mixed as in Figure 23.

If any two of the stator windings are reversed in the synchro unit under test, operation of switches 17 (labelled 0-180), 18 (labelled 60-240) and 19 (labelled 120-300) consecutively would cause the rotor $R_1 - R_2$ to rotate in a direction opposite to that indicated on the switch labels. That is, instead of the rotor rotating clockwise in 60° increasing increments to correspond with the switch labels, it would rotate counter-clockwise, in 60° decreasing increments exactly opposite to the labelling on the switches 17, 18, and 19 respectively. The reason for this is as follows:

a. If stator windings S_1 and S_2 are reversed as shown in Figure 19:

1. Then closing switch 17 actually shorts S_2 to S_3 (because of the crossed connections) as in Figure 11 and the rotor will therefore lock at a 120 or 300 degree position instead of 0° or 180° in accordance with the label on the switch.

2. Closing switch 18 actually shorts S_2 to S_1 as in Figure 10 and the rotor dial will lock at 60 or 240 just as the switch is labelled.

3. Closing switch 19 will short S_3 to S_1 as in Figure 12 and the rotor dial will lock at 0 or 180 (instead of 120 or 300 degrees as the switch is labelled).

It can be seen from the above that the dial is rotating from 120° to 60° to 0°, etc., instead of from 0 to 60 to 120, etc., is rotating in an opposite to normal direction. This will be immediately detected by closing switch 17 which will cause the dial to lock at a 120 or 300 degree position (instead of 0 or 180). By setting the drum 7 until either the 120 or 300 degree heading appears in sighting slot 6 and reading across horizontal indicia row 13 (Figure 7) there would appear (using vertical columns E or K, Figure 7) "Opposite rotation $S_1 - S_2$ in stator reversed."

The defect and remedy is thus made apparent.

b. If stator windings S_2 and S_3 are reversed (Figure 20):

1. Closing switch 17 will short S_2 to S_1 as in Figure 10 and dial will lock at 60 or 240 degrees (instead of 0 or 180 as labelled in Figure 1).
2. Switch 18 will short S_1 to S_3 as in Figure 12 and dial will lock at 0 or 180 (instead of 60-240 as labelled).
3. Switch 19 will short S_3 to S_2 as in Figure 11 and dial will lock at 120 or 300 (as labelled).

The synchro motor will therefore rotate in an opposite direction to that indicated by the labels on switches 17, 18 and 19 as these switches are consecutively actuated. Therefore by noting the synchro dial reading when switch 17 is closed (60 or 240 degrees in this case) and setting drum 6 with either of these headings (columns C or I of chart 8, Figure 7) appearing in the sighting slot 6, and reading across indicia row 13 it will be made apparent that stator winding S_2 and S_3 are reversed.

c. Stator windings S_1 and S_3 reversed (Figure 21):

- 40 In this case, closing switch 17 will actually short S_1 to S_3 and the synchro dial will lock at 0 or 180 degrees as in Figure 12 and will correspond to the switch label. However the rotor will still rotate in a wrong direction as will be noted by operating the other switches 18 and 19 in line with the above theory. Therefore, reading indicia row 13 (Figure 7) in connection with either columns A or G (corresponding to 0 or 180 degrees) it is found that coils S_1 and S_3 are reversed.
- 45

d. Stator windings $S_1 - S_2$, $S_2 - S_3$ and $S_3 - S_1$ mixed (Figure 22):

- 55 a. With the stator windings of the synchro under test mixed up in this manner, actuation of switches 17, 18 and 19 consecutively will result in the synchro rotor $R_1 - R_2$ rotating in the correct direction, that is to give progressively increasing dial readings, but the dial will not lock at positions corresponding to those labelled on the switches. The reasons for this is apparent from Figure 22 since:

1. Switch 17 will actually short S_2 to S_1 as in Figure 10 and the rotor dial will lock at 60 or 240 degrees (instead of 0 or 180 as labelled).
2. Switch 18 will short S_2 to S_3 as in Figure 11 and the dial will lock at 120 or 300 (instead of 60 or 240 as labelled).
3. Switch 19 will short S_1 to S_3 as in Figure 12 and the dial will lock at 0 or 180 (instead of 120 or 300 as labelled).

75 Therefore, by noting the synchro dial reading

when switch 17 is thrown (60 or 240) column 14, Figure 7 "Wrong indication, correct rotation" will indicate, in connection with either columns C or I, which are set in the sighting slot 6 that S_1-S_2 , S_2-S_3 and S_3-S_1 are reversed and should be corrected.

- e. Stator windings S_1-S_3 , S_2-S_1 and S_3-S_2 mixed

Here again the synchro rotor would correctly rotate to give increasing dial readings but the rotor dial will not lock at the points corresponding to the switch labels so that:

1. Switch 17 will short S_2 to S_3 as in Figure 11 with the rotor dial locking at 120 or 300 degrees (instead of 0 or 180 as labelled).
2. Switch 18 will short S_3 to S_1 as in Figure 12 and the dial will lock at 0 or 180 degrees (instead of 60 or 240).
3. Switch 19 will short S_1 to S_2 as in Figure 10 and dial will lock at 60 or 240 degrees (instead of 120 or 300).

Thus when switch 17 is thrown, the dial will lock at 120 or 300 degrees and by setting either column E or K (Figure 7) in the sighting slot 6, indicia column 14 will make apparent that coils S_3-S_2 , S_2-S_1 and S_1-S_3 are reversed and should be corrected.

It will be noted from Figure 8 that the analyzing chart 8 is provided with a band of color strips varying in width. These colors are red, green and amber corresponding to the colors of the indicating lights 3, 4 and 5 (Figures 1 and 7) on the instrument panel 1. The color strips are separated by black bands (to indicate no light) and the width of each color strip at any given point along the chart is proportional to the intensity of the corresponding indicating light.

In a preceding portion of the specification it was mentioned that the voltages existing in each winding S_1 , S_2 and S_3 respectively of the synchro stator vary in accordance with the curves shown in Figure 6 and that the indicating lights 3, 4 and 5 respectively, being connected across each of these stator windings gave a visual representation of these voltages by their respective intensities as the synchro rotor was rotated. In other words, if the synchro unit under test were correctly connected and in proper condition, as the rotor R_1-R_2 (Figure 3) was turned clockwise in 60 degree increments, and the drum 7 (Figure 1) was also correspondingly rotated so that columns A, C, E, G, I and K (Figure 7) alternately appeared in the sighting slot 6, then each of the indicating lights 3, 4 and 5 would vary so that their intensity would correspond to the width of the respective color band on the analyzing chart 8.

For this reason, the color band portion of the analyzing chart can be used to check the operation of a synchro transmitter unit in the following manner:

- a. The test instrument is connected to the synchro unit as before and the synchro rotor is then rotated in 30 or 60 degrees increments manually.
- b. The drum 7 is rotated so that the headings on the analyzing chart 8 (Figure 7) appearing in the sighting slot 6 correspond with the synchro dial readings.
- c. The intensity of the indicating lights 3, 4 and 5 is compared with the widths of the corresponding color bands on the analyzing chart 8 appearing in the sighting slot 6. They

should correspond and follow in sequence with the lights. If the color bands do not correspond with the lights an existing defect in the synchro circuit is made apparent and the visual indicia on the instrument panel 1 are referred to, for analyzing the defect as before.

6. SUMMARY OF TESTING PROCEDURE

Testing for opens in synchro stator circuit

Rotation of the synchro rotor either manually or by pressing of push-button switches 18 and 19 in sequence will cause all the indicating lights 3, 4 and 5 to simultaneously brighten and dim. The position of the synchro dial is noted at the positions in which all three of the indicating lights 3, 4 and 5 are out and the drum 7 is set so that the corresponding heading on analyzing chart 8 appears in sighting slot 6 of the test instrument and visual indicia column 11 on instrument panel 1 is read.

Testing for electrical short in synchro stator circuit

25 Synchro dial will lock at a position depending on which stator coils are shorted, and indicating light across the shorted coils will be out, the other two burning with equal intensity. Set drum and analyzing chart to correspond with synchro dial reading and refer to visual indicia row 12.

Testing for reversed stator windings

35 a. If any two stator windings are crossed, operation of switches 17, 18 and 19 in sequence will cause opposite rotation of synchro dial and the dial readings at which the rotor stops will not correspond to the labels on these switches. Set analyzing chart in sighting slot 6 to correspond with synchro dial reading and refer to visual indicia column 13 on test instrument panel 1 (Figures 1 or 7).

40 b. If all three stator windings are mixed, the synchro dial will rotate correctly, upon actuation of switches 17, 18 and 19 in succession, but the dial readings at which the dial stops will not correspond to the labels adjacent these switches (Figure 1). Set analyzing chart in sighting slot 6 to correspond with synchro dial reading and refer to visual indicia column 14 on the test panel 1.

Electrical zero alignment test

45 If, on actuating switch 17 (Figure 1) the dial on the synchro reads 0 degrees and blue indicating light 2 is on, and light 2 is out upon rotation of the synchro dial to 180 degrees, then set analyzing chart so that 180 degree heading appears in sighting slot 6 and refer to visual indicia row 15 on test panel 1.

General check of synchro transmitter operation

55 Rotate synchro unit and drum, comparing the sequence and intensity of indicating lights 3, 4 and 5 with the color scheme on the analyzing chart 8.

60 The test instrument comprising this invention has been shown and described in connection with a simple synchro circuit. It is obvious that it also can be used in testing the more complex synchro circuits employed such as a differential-synchro or control-transformer-synchro circuit since the theory of synchros applies equally well to the latter types of circuits.

65 The color scheme employed on the chart 8 and indicating lights 3, 4 and 5 are by way of illus-

tration only, since it is obvious that any convenient color scheme, or other indicating system similar to that described could be substituted.

It is to be understood that various modifications and changes may be made in this invention without departing from the spirit and scope thereof as set forth in the appended claims.

The invention described herein may be manufactured and used by or for the Government of the United States of America for governmental purposes without the payment of any royalties thereon or therefor.

What is claimed is:

1. An instrument for testing synchro circuits employing synchro units having a stator winding and a rotatable single-phase field winding comprising, in combination, an electrical test circuit including voltage-indicating means adapted to be connected across the stator windings of the synchro unit under test, and a circuit-defect analyzing device comprising a visual indicia scale having legends correlated with said voltage-indicating means and the movement of said synchro-unit rotor, and an adjustable chart having symbols pertaining to said synchro circuit and being adjustable to correspond with the various positions assumed by the synchro field winding, whereby defects made apparent by the voltage-indicating means and the behavior of the rotatable field of such synchro as the latter is rotated are visually analyzed and defined by the combined readings of said visual indicia legends and said symbols on said analyzing chart.

2. An instrument for testing synchro circuits comprising, an instrument panel having a plurality of defect-indicating visual indicia columns, an analyzing chart movably mounted on said test panel adjacent said visual indicia columns and in cooperative relation therewith, visual symbols on said analyzing chart aligned with said visual indicia columns, an electrical test circuit mounted on said test panel, for connection to the synchro under test, electrical indicating means in said test circuit and visible on said test panel, portions of said visual indicia columns having legends related to said electrical indicating means and the behavior of the synchro unit under test, which when read in connection with corresponding visual symbols on said analyzing chart define the nature of the defect in said synchro circuit indicated by said electrical indicating means.

3. An instrument for testing electrical circuits comprising an instrument panel, an electrical test circuit mounted on said instrument panel, electrically actuated indicating means in said test circuit, said indicating means being mounted on said panel for visual observance thereof, a sighting slot in said panel, a series of defect indicating visual indicia legends adjacent said sighting slot arranged in tabular form, an analyzing chart movably mounted underneath said panel and visible in part through said sighting slot, and a series of symbols tabularly arranged on said analyzing chart, said symbols denoting various components of the circuit under test, the portions of said symbols visible through said sighting slot being aligned with correlated portions of said visual indicia legends on said panel adjacent said sighting slot, whereby defects in the circuit under test made apparent by visual observance of said electrical indicating means may be defined and analyzed by visual reference to said legends on said test panel together with said symbols on said analyzing chart visible through said sighting slot.

4. An instrument for testing a synchro unit of the type having a stator winding and a rotatable field for open circuits, short circuits and circuit reversals comprising a circuit having electrical switch means for connecting the synchro field in parallel with said synchro stator winding, switch means for selectively electrically shorting adjacent phases of stator windings, electrically actuated visible indicating means connected across adjacent phases of said stator winding and in series with said rotatable field, and reversing switch means for reversing the relation between phases of the stator winding.

5. In an instrument for testing synchro units of the type having a polyphase wye-connected stator winding and a single-phase rotatable-field winding to which a dial having graduations is secured, the combination of an electrical test circuit having leads for connection to the windings of the synchro unit under test, voltage-indicating means and electrical switch means in said test circuit and a circuit-defect analyzing chart comprising columnarly arranged visual indicia representing various conditions of said voltage-indicating means and the rotatable field of said synchro unit under test, and an adjustable analyzing chart consisting of a number of columns of symbols, each of said columns having as a heading one of said graduations and the symbols of which denote the elements of the synchro windings under test, said analyzing chart being adjustable relative to said visual indicia so that each of said columns of symbols can be selectively aligned with said visual indicia corresponding to a given position of said synchro rotor, whereby defects made apparent by said voltage-indicating means and the behavior of said rotatable field winding are analyzed and defined by the combined readings of an appropriate column of said visual indicia and the portion of said symbols on said analyzing chart aligned therewith.

6. An instrument for testing synchro circuits of the type employing synchro units having calibrated dials, said instrument comprising a test panel having a plurality of defect-indicating visual indicia columns, an analyzing chart movably mounted on said test panel adjacent said visual indicia columns, said analyzing chart being provided with a plurality of columns of visual symbols each of which has as a heading one of the calibrations of a dial of a unit of a circuit to be tested, an electrical test circuit mounted on said test panel for connection to said synchro circuit under test, and electrical indicating means in said test circuit and visible on said test panel, actuation of said test circuit operating said synchro units in the synchro circuit under test and simultaneously energizing said electrical indicating means, said indicating means in said test circuit visually making apparent defects in said synchro circuit, whereby when said analyzing chart is moved to a position corresponding to the dial position of the synchro under test at which the defect is made apparent, portions of said visual indicia columns having indicia related to said electrical indicating means, will define together with a corresponding portion of said analyzing chart adjacent said legend, the nature of said defect.

7. An instrument for testing synchro units of the type having a polyphase wye-connected stator winding and a rotatable field having a dial having graduations and secured thereto, said instrument comprising an instrument panel, an electrical test circuit mounted on said panel, means for

15

electrically connecting said test circuit to the leads of said synchro unit under test, said test circuit including electrically actuated visual indicating means and switch means mounted on said instrument panel, said indicating means and said switch means being connected across adjacent phases of said polyphase stator winding in the synchro unit under test by said test circuit and one of said indicating means being connected in series with said synchro unit rotor, each of said switch means when closed, selectively electrically shorting the corresponding adjacent phases of said stator to which connected thereby to produce rotation of said synchro rotor in 60 degree increments, said indicating means at all times indicating the magnitude of the voltages across the corresponding phases of said stator to which connected, and defect analyzing means on said instrument panel in the form of visual indicia whereby defects made apparent by the operator of said switch and said electrical indicating means are visually analyzed and defined by said visual indicia.

8. A circuit tester comprising a plurality of visible indicia indicating a plurality of defects possible in a circuit to be tested, an analyzing chart movably mounted with respect to and adjacent said indicia and in cooperative relation therewith, various visible symbols on said chart having at various positions of said chart obvious relationship with said indicia, an electrical test circuit for connection with the circuit to be tested, electrical indicating means in said test circuit and simultaneously visible with said indicia and chart, portions of said indicia comprising legends related to said indicating means and the behavior of the circuit under test, which when read in connection with the corresponding chart symbols define the nature of a defect in said circuit indicated by said indicating means.

16

9. For use with a synchro unit having relatively rotatable single-winding and plural-winding members, apparatus for testing said unit for circuit continuity comprising a circuit including a source of energy and first switch means for connecting the single-winding member in parallel with the plural-winding member, second switch means for normally selectively effecting short-circuiting connections between predetermined windings of the plural-winding member, indicating means connected to each of the windings of the synchro unit, and reversing switch means for altering said normal short-circuiting connections between said predetermined windings.
10. Apparatus for testing a synchro unit for circuit continuity, said unit having relatively rotatable parts, one of said parts being of the plural-winding type, said apparatus comprising first switch means for effecting short-circuiting connections across adjacent windings of said one part, second switch means for connecting the other part in parallel with said plural-winding part, and individual indicating means connected across said adjacent windings and in series with the other part of said unit.
11. The apparatus defined in claim 10 further characterized by means for altering the short-circuiting connections across said adjacent windings.
